UNITED STATES PATENT OFFICE.

GEORGE W. HEATH, OF NEWARK, NEW JERSEY.

DEMOUNTABLE PEN-CLIP.

1,247,957.

Specification of Letters Patent. Patented Nov. 27, 1917.

Application filed April 30, 1914. Serial No. 885,351.

To all whom it may concern:

Be it known that I, GEORGE W. HEATH, a citizen of the United States, residing in the city of Newark, county of Essex, and State 5 of New Jersey, have invented certain new and useful Improvements in Demountable Pen-Clips, of which the following is a specification.

The portions of these clips which are visible are frequently made of gold or other precious metal and for economical reasons it is desirable in replacing the worn spring member to discard as little of the device as possible. Accordingly it is among the objects of the invention to provide a spring member of the least possible amount of material and to provide a simple means for securely and quickly attaching this spring member to the pen.

20 I attain this feature of my invention by fixedly attaching a channel member to the pen which member may be of some suitable strong metal and providing the more expensive spring member with a spring locking engagement with the channel member.

Various other objects and advantages of the invention will be in part obvious from an inspection of the accompanying drawings and in part will be more fully set forth in 30 the following particular description of one form of mechanism embodying the invention, and the invention further consists in certain new and novel features of construction and combination of parts hereinafter set forth and claimed.

Referring to the accompanying drawings:

Figure 1 is a longitudinal sectional view through a pen barrel showing a preferred embodiment of my invention mounted thereon in side elevation;

Fig. 2 is a transverse sectional view taken on the line 2-2 of Fig. 1 looking in the direction of the arrow;

Fig. 3 is a longitudinal sectional view taken on the line 3-3 of Fig. 1; and

Figs. 4 and 5 are respectively side and rear plan views of the clip detached from its support, the ball mounting of Fig. 4 being shown in section.

50 In the drawings there is illustrated a support in the form of a pen barrel 1 fixedly attached to the outside of which is a channel plate 2 having a configuration to fit the curvature of the outside of the barrel and 55 suitably fastened thereto as by means of the integral end prongs 3 and 4 upset in spaced apertures in the pen barrel.

This plate has its opposite longitudinal edges inturned to form the inwardly facing channel members 5 and 6. As this plate is 60 concealed by the spring member hereinafter described it may be made of some inexpensive metal and preferably is made of thin gage material so as to take up the least possible amount of space. 65

Removably positioned on the plate 2 is a spring pocket engaging member 7, one end of which is bent back upon itself to form an open bend 8 and to provide a relatively short base 9 adapted to be inserted between 70 and fit in the channels 5 and 6. This base is reduced in width to form edge shoulders 10 and 11, which engage the end of the plate adjacent the bend 8. The base is preferably of less thickness of material than the other 75 portion of this member for the portion of the plate forming the channels will compensate for any weakness resulting from thinning out this base portion and at the same time result in economy in metal used to form 80 this spring member and reduces the thickness of the attachment.

The end of the base opposite the bend is split to form outside spring fingers 12 and 13 which have a tendency to spring outward 85 into locking engagement with the channel members 5 and 6, leaving a middle portion therebetween to bear on the pen barrel. Preferably the ends of these fingers are out-turned as shown in Figs. 4 and 5 and offset 90 toward or into engagement with the barrel and to engage the adjacent end of the channel members and thus lock the member 7 to the plate 2. The projecting tongue 10' between the fingers 12 and 13 may also be bent 95 outward as shown in Figs. 1 and 4 to engage the barrel 1.

A spherical ball 14 is loosely mounted in the pocket engaging portion 15 of the member 7 adjacent its free end and has its upper 100 and under sides free for rolling engagement in any direction.

The plate 2 is suitably affixed to the pen barrel with the channelled side facing outward and the base of the spring portion is 105 inserted on the plate in position to have a spring tight fit between the grooves. Should it be desired to demount the spring member the fingers 12 and 13 are pressed toward each other by means of a pair of pincers 110 or other suitable tool and the spring member withdrawn to permit the insertion of a new member or to permit the insertion of a member of different character or metal.

By means of a device of this character it is possible to make the spring member of a minimum amount of precious metal and to replace the member when it becomes worn or damaged. The base portion may be thinned out, if desired, thus economizing in the use of the metal, while maintaining the necessary rigidity to the spring and at the same time the channel portion of the plate 1 provides a reinforcement to compensate for any weakening due to the thinned base.

By means of a device of this character it is possible to form the spring member of metal rolled to gage and stamped to shape and which may be readily bent to provide a two point contact, one of which contacts may provide a rolling engagement with the support as shown and the other of which 20 may provide a pinching engagement with the edge of the support.

The rolling contact provided by the ball reduces the scratching of the barrel when the clip is slid into the grooved channels.

25 While I have shown and described, and have pointed out in the annexed claims, certain novel features of my invention, it will be understood that various omissions, substitutions and changes in the form and design 30 tails of the device illustrated and in its operation may be made by those skilled in the art without departing from the spirit of the invention.

Having thus described my invention, I 35 claim:

1. The combination with a pen barrel, a plate fitting the outside of the barrel and fixedly attached thereto, said plate having its opposite edges inturned to form oppositely disposed channels, a demountable clip having a base portion adapted to be slidably inserted between said channels to face said plate, said portion having an outturned resilient end constituting a locking means for holding said member to the plate.

2. In a device of the class described, the combination with a pen barrel having a plate affixed thereto, said plate having its opposite longitudinal edges inturned to form oppositely disposed grooves, of a clip having a portion insertible between said grooves and means carried by said portion and movable relative thereto for springing the same into frictional engagement with the inturned edges of the plate, thus locking the clip from movement longitudinally of the grooves, said means adapted to be moved into unlocking position thereby permitting the dismounting of the clip.

60 3. In a device of the class described, the combination with a plate having opposite

edges turned in to form oppositely disposed channels adapted to be attached to a pen barrel, of a one-piece relatively light clip demountably attached to the plate and comprising a spring member and a base, said base being of a thickness less than the thickness of the spring member and insertible between said grooves, said grooves lapping the base and tending to compensate for the 70 weakening of the clip due to the thinned portion of the base.

4. The combination with a pen barrel, of a fastening device fixed to the outside thereof, of a clip having a base portion fastened to said device and having a spring member bent back upon the base, said spring member providing a two point contact spaced from the bend, one of said contacts being adjacent the fastening device and the 80 other being adjacent the free end of the spring member.

5. The combination with a pen barrel, of a fastening device fixed to the outside thereof, of a clip having a base portion fastened to said device and having a spring member bent back upon the base, said spring member providing a two point contact spaced from the bend, one of said contacts being adjacent the fastening device and the 90 other being adjacent the free end of the member, said other contact being a rolling contact.

6. As an article of manufacture, a clip construction comprising a plate having oppositely disposed channels, of a spring clip having a base portion insertible between said channels and having a resilient extension projecting beyond an edge of said plate, the projecting portion being bent from the general plane of the base portion about the end of the plate thereby to retain the clip in position on the plate.

7. As an article of manufacture, a pen clip comprising a plate having fastening prongs integral therewith and adapted to be upset in apertures in a fountain pen barrel, a spring member engaged frictionally by said plate to hold the same in place, said member having a plurality of spaced apart resilient pocket engaging portions and means for demountably fastening the member to the plate in positively fixed position relative thereto.

Signed at Newark in the county of Essex 115 and State of New Jersey this 24th day of April, A. D. 1914.

GEORGE W. HEATH.
